INFLATABLE HEAD REST OR SIMILAR ARTICLE

William M. Emery, 44 Pittsford Way,
New Providence, N.J.

Filed Sept. 6, 1960, Ser. No. 62,024

Term of patent 14 years

(Cl. D3—9)

FIG. 1 is a top view of an inflatable head rest or similar article, showing my new design;

FIG. 2 is a front elevational view; and

FIG. 3 is a rear perspective view thereof.

I claim:

The ornamental design for an inflatable head rest or similar article, as shown.
